TAPE CUTTER HAVING MEANS TO ADJUST THE LENGTH OF THE TAPE FED BETWEEN CUTS.

Anthony Abbenante, Ozone Park, N.Y.
Filed Mar. 1, 1954, Ser. No. 413,130

2 Claims. (Cl. 83—245)

This application relates to an improved tape cutter for operation in association with a tape feeding device such as a sewing machine or the like.

The invention is directed to providing means for automatically cutting off predetermined lengths from a continuously fed ribbon or tape of cloth, paper, plastic material, metal foil and the like. It is a principal object to provide a device for automatically cutting predetermined lengths of tape and adapted for automatic or manual operation at will.

It is another object to provide a device which is relatively inexpensive to manufacture, simple to operate, and completely reliable in operation for cutting predetermined lengths of fabric accurately, neatly, and wholly automatically.

Other and further objects and advantages of the invention will become apparent from the following description taken together with the drawing. The scope of the invention is defined in the appended claims.

It is intended that the device embodying the invention will be generally employed in association with a sewing machine. As the tape to be cut by the present tape cutter is sewed by the sewing machine it will be fed through the tape cutter. As predetermined lengths of tape pass through the tape cutter, they will be automatically cut. The tape cutter is disposed to be driven via a suitable mechanical arrangement by the driving motor of the sewing machine, generally in coordination with the operation of the sewing machine. The tape cutter is adapted for manual operation at the will of the operator to cut the tape at any desired point.

FIG. 1 is a front elevational view of a device embodying the invention and an associated driving mechanism.

FIG. 2 is a rear view of the device shown in FIG. 1.

FIG. 3 is a side view of the device taken on lines 3—3 of FIG. 2.

FIG. 4 is a sectional view taken on lines 4—4 of FIG. 1.

FIG. 5 is a sectional view taken on lines 5—5 of FIG. 1.

FIG. 6 is a sectional view taken on lines 6—6 of FIG. 5.

FIG. 7 is a sectional view taken on the lines 7—7 of FIG. 5.

In FIG. 1 is shown a driving mechanism for the tape cutter embodying the invention. This mechanism includes a shaft 10 journaled in the upstanding ends of frame 11. Frame 11 is securely clamped by C-clamps 12, 13 to the table T which may be a sewing machine table. A pulley 14 is carried by shaft 10 and is driven by a belt B from a suitable driving power source, such as the driving motor of an associated sewing machine. Pulley 14 is held in abutment with wheel 15 by a spring 16 tensioned by collar 17. Collar 17 and wheel 15 are both secured by set screws to shaft 10. Pulley 14 is thus frictionally engaged with wheel 15. Shaft 10 carries a hexagonal collar 18 in the end of which is eccentrically disposed the pin 19. Pin 19 is engaged in the link 20. Link 20 is connected to a one way clutch member 21 via pin 22. Clutch member 21 imparts movement in only one direction to the shaft 23 as shown by arrow 24 in FIG. 3. Shaft 23 carries the gears 25 and 26 disposed as shown in FIGS. 1 and 2. Gear 25 engages gear 27 which is carried by shaft 28. Shaft

2

28 carries and turns the feed roller 29 shown best in FIG. 2.

In FIG. 2 roller 29 is shown closely disposed to table 30. Between roller 29 and the top of table 30 passes tape A which is moved by roller 29 from rear to front of the tape cutter. A pair of pins 31 are disposed in shaft 28. The pins may be engaged by the end of release bell-crank 32 which may be pivoted to raise roller 29 and release tape A when it is desired to pull the tape freely through the tape cutter. See FIGS. 2 and 3. The shaft 28 journals in a pair of slots S in the upright frame members 33, 34 so that the shaft 28 and roller 29 can be lifted by release bell-crank 32. A knife 35 is disposed vertically between the frame members 33, 15 34 and is guided in movement there between to sever the tape A in response to actuation of a solenoid disposed in housing 36. The solenoid is electrically actuated by energy supplied from a suitable source and delivered to the solenoid through conductors 37. Conductors 37 are 20 in circuit with a relay type switch 38 which operates to open and close the circuit leading to the power input conductors 39 embodied in cable 40 and connected to the power plug 41. Switch 38 is operated whenever plunger 42 contacts switch element 43. The internal details of 25 switch 38 and the solenoid in housing 36 are not shown since they are entirely conventional and do not constitute the present invention. Switch 38 is provided with electrical terminals E as indicated in FIG. 5.

In FIG. 7 the several switch actuating elements are 30 shown on an enlarged scale. Plunger 42 is actuatable in one way by manually depressing pin 45 which tilts crank element 44 and causes plunger 42 to move into contact with switch element 43. Plunger 42 is also actuatable automatically. It will be noted that plunger 42 is supported by a cam follower 46 pivoted on a pin 47. A spring 48 shown best in FIG. 5 is tensioned torsionally when the cam follower 46 moves the plunger to actuate switch 38. The spring operates to restore the plunger and cam follower to their original positions. Cam follower 46 is responsive to rotation of cam 49. Cam 49 is carried by a shaft 50 which also carries friction wheel 51 slidably keyed thereto. Friction wheel 51 is rotated by its frictional contact with the face of disc 52. Disc 52 as shown in FIG. 4 is a circular member with a rubber or rubberized face. Disc 52 is carried by shaft 28 and is 35 rotated therewith. Shaft 28a also carries the gear 53 which engages gear 26 mounted on shaft 23. The speed of rotation of friction wheel 51 depends on its position radially with respect to the center of disc 52. This position is determined by the placement of the grooved hub 54 of wheel 51 along shaft 50. A pin 55 rides in the annular groove 56 in hub 54. Pin 55 is movable laterally in slot 57 of the stationary plate 58.

In FIG. 6 is shown the pin 55. A knurled knob 59 and dial 60 are operatively connected to pin 55 and permit lateral movement of the pin to locate hub 54 and wheel 51 in any desired position within the limits of disc 52. A pinion 55a fixed to pin 55 engages a stationary rack 58a on plate 58 and said pin may be caused to move laterally in slot 57 by rotating knob 59. A locking pin 61 carried by a bracket 62 is provided and serves to lock dial 60 after the position of wheel 51 is set. In order to release wheel 51 from frictional engagement with disc 52 there are provided the slotted fingers 63 which are secured on shaft 64. A handle 65 is provided to partially rotate shaft 64 which causes fingers 63 to move shaft 50 just enough to disengage the wheel 51 and disc 52. A spring 66 is compressed on downward movement of handle 65 and serves to restore handle 65 and shaft 64 to their original positions. Spring 66 also assists in maintaining the frictional contact between discs 51 and 52.

In FIG. 5 is shown a knurled knob 67 and a pin 68.

Knob 67 serves to rotate the shaft 50 until the cam 49 is located at a particular position with respect to cam follower 46 which determines the point from which measurement of predetermined lengths of tape begins. The rotation of knob 67 is limited by pin 68 which the radially projecting portion of stop element 69 contacts at the limit of rotation. Stop element 69 is located at the base of knob 67.

A roller shaft 70 is provided with supporting pins 71. These pins together with the roller shaft 70 serve to guide the tape A entering under roller 29. The discs 72 at the ends of shaft 70 prevent disengagement of the shaft from pins 71. A clamping bolt 73 provided with a handle 74 is threaded in the bottom frame member 75 and serves to secure the tape cutter to a table T'. A horizontally disposed frame member 76 is disposed on the side frame members 33, 34 and serves to support the solenoid housing 36. A counter 77 is operatively connected to knife 35 to indicate the number of times the knife is lowered. Each lowering of the knife is counted as one predetermined length of tape cut by the tape cutter.

To operate the tape cutter, certain adjustments must be made. If desired tape A can be first threaded between roller 29 and table member 30. Roller 29 is raised slightly to facilitate insertion of the tape by manually pulling the bell-crank 32 forward. When bell-crank 32 is released roller 29 returns to its original position. The cam 49 is located at its initial position by rotation of knob 67. The dial 60 is calibrated in terms of tape length so that by rotation of the attached knob 59 the disc 51 can be positioned relative to disc 52 to allow passage of a predetermined length of tape before the knife 35 is actuated. Actuation of knife 35 occurs automatically and depends on the passage of a predetermined length of tape passing under roller 29. Roller 29 is caused to rotate by the driving means for belt B which is operatively connected to the roller 29 via shaft 10, link 20, clutch 21, and gears 25 and 27. During the course of rotation of roller 29 on shaft 28, the cam 49 at one of its stepped points causes cam follower 46 to move plunger 42 into contact with switch element 43. Switch 38 is then closed causing electric current to flow through the solenoid in housing 36 to lower knife 35 until it severs the tape. The knife is raised as the cam 49 continues to rotate causing the electric circuit to open. To actuate the knife 35 at any desired point regardless of the position of the cam 49 with respect to cam follower 46, the pin 45 is pressed down manually to tilt the crank element 44 and cause plunger 42 to close the electrical circuit which actuates knife 35. Whenever the tape is thus cut manually, the cam 49 must be reset to its initial position if automatic cutting of the length of fabric set by dial 60 is to be accomplished on the next cut. Otherwise, the tape passing under roller 29 will be cut automatically on the next cut but the length of cut tape will be less than the predetermined length. Succeeding lengths of tape will be cut automatically at the predetermined length set on dial 60.

The present invention is particularly adapted for cutting tapes, ribbons, and the like. It will be apparent to those skilled in the art that the invention is readily adapted to cutting narrow filaments such as threads and cords as well as bands of extended width in sheet form. Thus the term "tape" is to be construed in the specification and claims as generic and placing no limit on the width of material cut by a device embodying the invention. Also no limit is placed on the nature of the material cut by the cutting device. The cutter is readily adapted to cut cloth, paper, plastic material, metal foil, and other thin sheet, ribbon, or filamentary material of organic and inorganic origin.

Although a single preferred embodiment of the invention has been disclosed it is desired that this shall be construed as only illustrative of the invention. Many changes and modifications are possible without departing from the spirit of the invention. The scope of the invention shall be regarded as limited only by the appended claims.

I claim:

1. A tape feeding and cutting device comprising in combination, a drive mechanism operatively connected to a feed roller, said mechanism including a reciprocatable link and one way clutch, to drive the roller in one direction, said roller being disposed to pass tape through the device, a friction disc operatively connected to the roller, a friction wheel driven by said disc and means operative to adjust said friction wheel to selective predetermined positions with respect to the axis of the disc to control a drive connection between the friction wheel and said cam means for manually adjusting the position of said cam with respect to said cam follower, a switch disposed for periodic actuation by the cam follower, and a knife operatively connected to and controllable by an electrical circuit including said switch, to cut lengths of tape determined by the position of said wheel relative to the axis of said disc, a calibrated dial being provided for the setting of the said wheel in a position to fix the length of tape cut by the knife, said cam including a stepped portion which is engageable by the cam follower, said switch being actuated when the cam follower reaches said stepped portion of the cam.

2. A tape feeding and cutting device comprising in combination, a drive mechanism operatively connected to a feed roller, said mechanism including a reciprocatable link and one way clutch, to drive the roller in one direction, said roller being disposed to pass tape through the device, a friction disc operatively connected to the roller, a friction wheel drive by said disc and means operative to adjust said friction wheel to selective predetermined positions with respect to the disc to control speed of rotation of the wheel, a cam, a cam follower, drive connection between the friction wheel and said cam means for manually adjusting the position of said cam with respect to said cam follower, a switch disposed for periodic actuation by the cam follower, a knife operatively connected to and controllable by an electrical circuit including said switch, to cut lengths of tape determined by the position of said wheel relative to the axis of said disc, a calibrated dial being provided for indicating the setting of the said wheel in a position to fix the length of tape cut by the knife, and means manually operable to actuate the knife at will.
